(57) **CLAIM**

The ornamental design for a cable spacer, as shown and described.

DESCRIPTION

FIG. 1 is a perspective view of a first embodiment of a cable spacer illustrating my new design;

FIG. 2 is a left side elevation view thereof, the right side being a mirror image thereof;

FIG. 3 is a front elevation view thereof, the rear elevation view being a mirror image thereof;

FIG. 4 is an enlarged, top plan view thereof, the bottom plan view being a mirror image thereof;

FIG. 5 is another perspective view of a portion thereof;

FIG. 6 is another perspective view of the portion thereof;

FIG. 7 is an enlarged perspective view of the portion thereof;

FIG. 8 is another enlarged perspective view of the portion thereof; and

FIG. 9 is another enlarged perspective view of the portion thereof.

FIG. 10 is a perspective view of a second embodiment of a cable spacer illustrating my new design;

FIG. 11 is a left side elevation view thereof, the right side elevation view being a mirror image thereof;

FIG. 12 is a front elevation view thereof, the rear elevation view being a mirror image thereof; and,

FIG. 13 is an enlarged, top plan view thereof, the bottom plan view being a mirror image thereof.

The broken lines appearing in FIGS. 2, 3, 7, 8, 10 and 13 illustrate portions of the article that form no part of the claimed design. The broken lines appearing in FIGS. 1, 8 and 9 are shown for the purpose of illustrating the environment in which the article embodying the design is used.

The cable spacer is shown with a symbolic break in its length in FIGS. 10-12. The appearance of any portion of the article between the break lines forms no part of the claimed design.

1 Claim, 5 Drawing Sheets
